HEATER HOUSING FOR HAIR CURLERS

John L. Benty, Scotch Plains, and Daniel Friedman,
Edison, N.J., assignors to Clairol Incorporated, New
York, N.Y.

Filed Nov. 9, 1970, Ser. No. 25,886

Term of patent 14 years

Int. Cl. D28—03

U.S. Cl. D86—10

FIG. 1

FIG. 2

FIG. 3

FIG. 4

FIG. 1 is a front perspective view of a heater housing for hair curlers showing our new design,

FIG. 2 is a side view thereof and,

FIG. 3 is a rear view thereof.

FIG. 4 is a top plan view thereof.

The bottom of the heater housing for hair curlers is substantially plain and flat.

We claim:

The ornamental design for a heater housing for hair curlers, substantially as shown and described.
